LEVEL 1

Charles M. Titus

UNITED STATES PATENT OFFICE.

CHARLES M. TITUS, OF ITHACA, NEW YORK.

DUMPING-WAGON.

SPECIFICATION forming part of Letters Patent No. 329,346, dated October 27, 1885.

Application filed April 13, 1885. Serial No. 162,018. (No model.)

To all whom it may concern:

Be it known that I, CHARLES M. TITUS, a citizen of the United States, residing at Ithaca, Tompkins county, New York, have invented 5 an Improved Dumping-Wagon, whereof the following is a specification, reference being had to the accompanying drawings.

My invention relates to a four-wheeled wagon, and to a box made in two parts, one resting mainly on the fore and the other on the rear wheels; and my invention consists in the adaptation of the dumping-divisions to a common wagon and to its reach, and to the means of retention in place and of dumping the divisions of the box, as will be apparent as I describe my invention.

Figure 1 is a view from above, or a ground plan of my wagon. Fig. 2 is a side elevation, and Fig. 3 is a view of the fore box and its position when dumped. Figs. 4 and 5 show an adjustment of divisions of the box and of clamps differing somewhat from the other figures.

In the figures, *a* is the front division of the box, and *c* is the rear part of the box, and *b* is the rear axle, to which the rear division of the box is hinged; and *d* is a second bolster, to which the anterior division is hinged, and is placed in rear of the usual front bolster, and is attached to it by connecting rods or pieces *d'*. 25 To support this second bolster in its place, I make the wagon-reach *e* quite stout, and strengthen it by the metallic truss *e'*, as shown, beneath the reach. It will be noticed that a small section of the fifth-wheel *f* of the front 30 axle is indicated as resting on this iron truss bracing in Figs. 2 and 3, but as it would obscure the parts shown in Fig. 1, it is omitted in that figure. A secondary iron bar segment of a fifth-wheel is used, on which, as is common, the 35 ends of the two bolsters *d* *d''* rest, my modification being so to form it that it shall reach my rear bolster, *d*. These iron fifth-wheel segments are omitted lest they obscure the drawings. Just in rear of this second bolster will 40 be noticed the stout hinges *g*, on which the front division of my wagon-box rests, and by which it is held. This division has a front end-board, *h*, but no rear end-board, since, when in use, the front end-board of the rear 45 box-division *h'* is all that is needed. The rear box-division *c* is hinged to the bolster of

the rear axle by the hinges *g'*, and this box-division and its hinges act as in any two-wheeled cart. Next is the provision I make for the use of a reach in my wagon, and it will 55 be noticed that at *i* is a hinged piece in the bottom of the front box-division, directly over the reach. In Fig. 1 it is closed down in its place, because the box is shown in the position to receive its load; but in Fig. 3 it is open, 60 because the box is in the position of being dumped, when this hinged part rests on the reach, which thus becomes the self-acting means of opening it.

At *j*, Fig. 1, there is shown a lever-clamp 65 that fastens the two divisions of the box together. Its shape is not very essential; but its point is wedge or cam shaped, so that it closes the boxes together tightly or snugly to each other. This is shown only on the upper side 70 of Fig. 1; but a similar one is used on the lower side of that figure, if needful; or one can be placed to act by one lever on each side of the hinged piece *i*, in which case it is fast to the middle of the rear box-division front end-board, and its staples are in the bottom of the front division of the box. It is important that the clamps be made strong, and to close the two divisions of the box firmly together; also, 75 it will be noticed that a bolster-shaped cross-piece, *m*, is attached to and moves with the rear division of the box, and which, when the rear box-division is returned to the loading position, rests on the reach. The front-axle bolster acts as a guide for the loading position 80 of the front box-division; thus the box-divisions are self-adjusting to each other on the horizontal level, and for the clamps to act. The reach is made of a stout top wood strip, 85 *n*, extending from the usual king-bolt of the front axle to and through, in the usual manner, the usual place between the rear bolster and axle; but I add to it a stout iron truss, *n'*, which begins at or embracing the king-bolt, or close to it, and has a stud-block, *n''*, under 90 the additional bolster, near the front axle, and goes backward to a stud-block, *n'*, under the bolster cross-piece *m*, and to near or through the aperture in the rear bolster and axle, where it ends. By this means I make 95 a wagon-reach fitted to the demands of the wagon I have described. It is advisable to 100

make the tie-bolt rods that hold the additional bolster d to the front bolster, d'' , of iron, but they may be made of wood; and in the adaptation of a common wagon to my devices the front bolster, d'' , is perforated for these bolt-rods, that when the additional or second bolster may be put on or taken off of the wagon the reach may not be removed; but as it may be shorter than the usual length in farm-wagons, it can be taken out and a common one substituted when the box-divisions have been removed. The bolt-rods being unloosed, the additional bolster is taken off.

To fit the wagon for the ready adjustment of my devices, the segmental fifth-wheel of wagons constructed as usual should be made to be easily adjustable, that the cross-segment of the fifth-wheel may be taken out and easily put in the place (shown in the figures) it has in my reach.

Thus by my devices shown and described I make a dumping-wagon box, with two divisions or boxes, adapted to the transportation and the ready unloading of various articles—such as manure, earth, sand, &c.—and for use in excavating, road-repairing, and like uses. The bolster d is bolted to and through the reach and the stud-block n'' . The box divisions a and e may be made to fit one within the other, as shown in Figs. 4 and 5. The box e in Fig. 4 is represented to be adjusted to have its sides and end-board h go a few inches into the rear end of the division a . This folding of one division into the other makes a stouter junction of the boxes together, and also allows a better plan for the clamps of the divisions. The plan is shown to be that staples are attached to the division e , which pass, when the boxes are put one in the other, through apertures in the bottom of the division a a certain distance, when the rod j' , by its handles from either side, is moved, and this causes the hooks j'' , attached to this slide-rod j' , to enter

the staples, and thus lock the divisions together. This rod is, by a spring, self-acting when it is desirable thus to make it.

What I claim as my invention is—

1. In a dumping-wagon, the second or additional front bolster attached to the front bolster, and to which second bolster the front division or box is hinged, in combination with the reach n , as set forth.

2. The reach e' , made of the reach proper, n , in combination with the truss-bracing rod n' , and with the stud-blocks $n''' n^4$, and adapted to sustain the additional bolster d and the bolster cross-bar m , as shown and described.

3. A second bolster, d , secured by the rods $d' d''$ to the front bolster, and constituting with the front bolster a fixed resting support for the division a of the wagon-box.

4. The cross-bar m , secured to the reach n , in combination with the rear axle, to which the reach n extends, the said cross-bar and axle constituting the supports of the rear division of the box, as set forth.

5. A two parted or divided wagon-box, each division dumping in a separate cart-like manner, in combination with and adapted to a wagon with a reach, as set forth.

6. A wagon with dumping division-boxes a and e , suited to a wagon-reach by means of a hinged piece in the bottom of the front division of the box, whereby a pit for the reach is made, as shown and described.

7. A lever, j , or cross-rod j' , provided with hook-shaped or inclined tightening-surfaces, whereby when the lever or rod is in the closed position for holding the boxes or divisions together these surfaces act as tightening-wedges, thus making a firm locking together of the divisions.

CHARLES M. TITUS.
